Specification for Design.

Patented Feb. 7, 1922.

Application filed August 17, 1921. Serial No. 493,187. Term of patent 14 years.

To all whom it may concern:

Be it known that I, BENJAMIN E. MEACHAM, a citizen of the United States, residing at Lorain, in the county of Lorain and State of Ohio, have invented a new, original, and ornamental Design for Ovens, of which the following is a specification, reference being had therein to the accompanying drawings.

My invention relates to a new and ornamental design for ovens as shown in the accompanying drawing, in which the figure is a perspective view showing my new design.

I claim:

The ornamental design for an oven, as shown.

In testimony whereof, I hereunto affix my signature.

BENJAMIN E. MEACHAM.
